UNITED STATES PATENT OFFICE

172,028

HOBBYHORSE OR SIMILAR ARTICLE

William D. Hull, Chicago, Ill.

Application April 20, 1953, Serial No. 24,580

Term of patent 14 years

(Cl. D34—15)

To all whom it may concern:

Be it known that I, William D. Hull, a citizen of the United States and a resident of Chicago, Cook County, Illinois, have invented a new, original, and ornamental Design for Hobbyhorse or Similar Article, of which the following is a specification, reference being had to the accompanying drawing, forming a part hereof.

Figure 1 is a side elevational view of a hobbyhorse or similar article, showing my new design. Figure 2 is a top plan view thereof.

The opposite side of the hobbyhorse, not shown, has substantially the same appearance as the side shown in Figure 1.

The rear elevation of the neck of the horse is a plane surface which has a conventional appearance. The front elevation of the tail portion of the horse is a plane surface which has a conventional appearance.

I claim:

The ornamental design for a hobbyhorse or similar article, substantially as shown and described.
